EARRING

Louis Hoffman, Brooklyn, N. Y.

Application November 13, 1943, Serial No. 510,094

9 Claims. (Cl. 63—14)

My invention relates to an earring and more particularly to an arrangement for securing an earring against loss.

One of the objects of my invention is a simple and inexpensive arrangement whereby an earring can be secured to the lobe of the ear.

Another object of my invention is the provision of an arrangement whereby an earring can be readily secured to and removed from its fixed association with the lobe of the ear.

Another object of my invention is the provision of means for securing an earring in position on the ear whereby any unintended or undesired tendency of the earring to drop off the ear will automatically cause the securing action of the securing means to act with increased effectiveness.

For the attainment of these objects and such other objects as may hereinafter appear or be pointed out, I have illustrated an embodiment of my invention in the drawing herein:

Figure 1 is a side elevational view of my earring assembly detached from the ear;

Figure 2 is a vertical section through the assembly of Figure 1 secured to the ear;

Figure 3 is a top elevational view of Figure 1;

Figure 4 is a section taken on line 4—4 of Figure 1 looking in the direction of the arrows; and

Figure 5 is a perspective view of the securing member separated from the earring.

Upon viewing Figures 1 and 2 it will be observed that the device therein illustrated is comprised of an ear-embracing member A shown in Figure 2 in its ear-embracing position and a member B shown in Figures 1 and 4 as adjustably engaged with the member A and shown in Figure 2 as in its active or operative position to secure the member A against accidental removal from the ear.

For the convenience of reference I shall refer to the member A as the ornament carrying member and to the member B as the earring-securing member, and I will now proceed to describe the construction of the former. It may be formed from any preferred or desired material which will serve the purposes herein set forth, such as metal, plastic or the like and in any preferred or desired manner. I find that the objects of my invention are effectively attained when the member A is formed or stamped from sheeted material such as metal to provide a strip which is bent to a shape and conformation such as shown in the drawing.

Upon comparing Figures 1 and 4 it will be observed that the member A is comprised of the

portion 20 which carries or presents the visible or decorative portion of the earring to the front thereof, the portion 21 in which the aforementioned securing member B is carried, and the U-shaped section which connects the two portions 20 and 21 and which for convenience of disclosure will be identified as comprised of two legs 24 and 25 and the connecting bight 26. The relative dimensions of the several parts of the disclosed embodiment can be calculated from Figure 2 by reference to the thickness there given to the lobe of the ear and to which reference character L has been applied.

The U-shaped portion, comprised of the parts 15: 24, 25 and 26, is shown as formed from a flat strip of metal or other satisfactory material and is of relatively narrow width. While its width may for general purpose be a matter of choice, it is contemplated that legs 24 and 25 be capable of 20 being spread apart to engage the member A about the lobe of the ear and that they tend to return to their normal position when such engagement is effected, the material of which the parts 24, 25 and 26 are made and their dimensions should be such as to permit these parts to function in this manner.

The ornament carrying portion 20 is shown as extending upwardly from the upper end of leg 24. Its perimeter is shown as circular, its diameter as much greater than the aforementioned width of the leg 24 and its shape is contoured so as to be concavo convex with the convex face 32 presented inwardly or to the rear and the concave surface 31 presented outwardly or to the 35 front all for the purposes of presenting a relatively large area of contact to the ear with a minimum of irritation. The concave face 31 may serve as or may carry the decorative or ornamental portion of the earring which is visible to the 40 onlooker.

The member 21 extends upwardly from the upper end of the leg 25. While I show its perimeter as round or circular, this will be understood merely as exemplifying one of the many shapes that may be given to this extension. Its width or diameter is also greater than the width of the leg 25 as given in the drawing for reasons that will be pointed out as this description proceeds.

The securing or locking member B is also 50 formed preferably of a strip of material bent to a shape and a construction to function as more fully to be described by reference to the various figures of the drawing. Upon viewing Figures 3, 4 and 5 it will be observed that the strip from which the locking member B is formed is shown

as of uniform width throughout. The reason for this will appear shortly. This strip is preferably made of a resilient material. Its intermediate portion is bent into the ringlike conformation shown at 40 which forms one end of the resulting structure. This ringlike portion or head 40 terminates at points 40' and 40² which are normally in close adjacency however to leave a slight space 41 between these points when the parts of member B are in their normal relation (see Figure 5). This ringlike portion 40 can be compressed to the limit permitted by the space 41. This limit is reached when the points 40' and 40² contact.

Extending from these terminals or points 40' and 40² of the ringlike member 40 and in the same direction are the two portions which I shall hereafter term "fingers."

It will now be pointed out that the enlarged head or portion 21 of the member A which extends upwardly from the leg 25 is provided with opening 30 shown as rectangular and whose width is as close to that of the strip from which the locking member B is formed as is permitted, however without interfering with the free sliding movement of the member B through this opening 30. The height of this opening reflects the manner in which the two fingers function and will therefore be described by reference to the thickness of the member B as measured on Figure 5 in the plane through the neck 40'-40² wherein the member B is shown in its normal (i. e. uncompressed) condition. It will suffice for the moment to state that the height of opening 30 is slightly less than that aforementioned thickness so that when the element B is assembled with element A (see Figures 1 and 2) the former will always be under compression.

Reference has been made to the fingers which extend from the ringlike member 40. These fingers will be described by reference to Figure 5 wherein they are each shown as comprising a relatively straight portion 42 or 44 which extends outwardly from terminals 40' and 40² and which terminates in curved portion 43 and 45 respectively so that the two fingers can be characterized as hooklike in conformation. Upon viewing Figures 1, 2 and 5 it will be observed that the curved or hook portion 45 is formed larger than the hook portion 43. This difference can be expressed as resulting from the fact that hook portion 45 is bent to have a larger radius of curvature than has the hook portion 43, although this is not to be taken to mean that these portions are bent precisely to a circular conformation. It will also be observed by reference to Figure 5 that the straight portion 42 is shorter than portion 44 and as a result the hooklike end 45 of the latter is positioned generally further removed from ringlike member 40 than is hook 43.

The portions 42, 43, 44 and 45 are given a normal permanent set such as shown in Figure 5. It will be seen upon viewing Figure 5 that the finger portion 42 has a set at a downward angle somewhat as shown in that figure whereas the finger portion 44 has a set at an upward angle and that in the normal uncompressed position of the locking member B (when disassembled from the earring as in Figure 5) the terminal end of the hook 43 at the end of the finger portion 42 extends downwardly beyond the terminal end of the curved end 45.

It has already been stated that the opening 30 in the member 21 is about the width of the two

fingers and that its height is such that when the locking member B is inserted therethrough, the top and bottom edges of the opening 30 in portion 21 of member A will always directly impose a compression action on the members 42 and 44 and indirectly a compression action upon the ring member 40 and which compression action will increase as the member B is entered further through the opening 30 because these portions 42 and 44 are given a normal set of divergence as shown in Figure 5. The initial compression will distort ring 40 so that the terminals 40' and 40² will be forced into contact. Any increase in compression, which as stated will result when the member B is moved further through opening 30, will cause the finger portions 42 and 44 to be flexed about this line of contact to reduce the angle therebetween and bring them into closer adjacency and in so doing will cause the curved part 43 to move relatively to the curved part 45 from its position of Figure 1 to its position of Figure 2.

The member B of Figure 5 is assembled with member A of the other figures in any preferred or desired manner as by forcing the straight finger portions 42 and 44 into close adjacency and thereby causing the hooked or curved portion 43 to nest entirely within the curved portion 45 even beyond the relative position of these two as shown in Figure 2 where the two portions 42 and 44 are shown only partly forced toward each other. In this distorted or compressed position of the parts of the member B, the member B can be manipulated so that the outer free end of the curved or hooked portions 43 and 45 can be entered into and through the opening 30 by a gradual angling movement of the member B beginning with a position where the member B is just presented with these terminal portions in registration with opening 30 for initial entry thereof into said opening and the member B then gradually angled until the parts assume a relation somewhat as shown in Figure 1 of the drawing.

It will be again repeated that the height of the opening 30 is such that the leg portions 42 and 44 will always be held under compression and that the degree of compression will depend upon the extent to which the member B is moved inwardly through the opening 30. It will be here pointed out that because of this increasing compression as the members move outwardly the tendency will be for the member B to move inwardly to its position of Figure 1.

The securement to the lobe of the ear L is effected as follows: the legs 24 and 25 are spread apart sufficiently so that the assembly of Figure 1 can engage about and embrace the lower end of the lobe L of the ear. In this operation the member B will assume the position shown in Figure 2 due to the thickness of the interposed ear lobe L. In this position the compression or distortion of the legs of the member B will be considerably greater than that of its position in Figure 1 and therefore the tendency of the member B to move inwardly toward earring 20 will have been considerably increased. As a result the member B will tend always to move inwardly and in so doing to engage the lobe of the ear with an increasing pressure and the curvature of the portion 45 is significant because it not only gives an increased engagement with the lobe of the ear but also decreases any tendency to irritate.

The member B is free to angle within the opening 30 and the significance of this will now be

pointed out in assuring the securement of the earring against accidental dropping off or separation from the lobe of the ear. Any tendency of the earring to separate from the lobe of the ear will be by a downward movement of the earring assembly relatively to the lobe (see Figure 2). This downward movement will tend to swing the member B clockwise in its position of Figure 2 and in so doing will impose an increased pressure upon the leg portions 42 and 43 which will resist this relative downward movement of the assembly and increase the pressure upon the ear lobe. This increased pressure will be somewhat increased by the fact that the extreme inner end of the curved portion 45 which is in engagement with the lobe of the ear, will tend to move in an arc which will bring it closer to the portion 20 of the earring.

The curved parts 43 and 45 are flexible as well as yieldable. The pressure applied thereby to the lobe of the ear is a yieldable one and for a substantial length.

It has been pointed out that upon the outward movement of the locking member B from its position in Figure 1 to its position in Figure 2 the curved portion 43 is given a relatively upward movement to fully nest within the curved portion 45. I prefer that the parts be so formed and related that the end of 43 have a wiping contact with the end of the curved portion 45 during this movement. I have attempted to show this contact in Figure 1.

The assembly shown in Figure 1 is applied to the ear as follows: The element B is fully retracted to its position of Figure 2. This retraction can be facilitated by compressing either the ringlike portion 40 or pressing together the portions 42 and 44. The legs 24 and 25 are then spread apart sufficiently so that the assembly can be freely received over the edge of the lobe of the ear. Upon release, the legs 24 and 25 will then resume their normal position as shown in Figure 2 and the lobe of the ear will be engaged by and between the upper portion 20 of the leg 24 and the curved portion 45 of the member B. Since the portions 42 and 44 are under substantial compression in their position of Figure 2, there will be a tendency of the member B to move inwardly and this tendency will serve to apply a continuous yieldable pressure to the ear which has a tendency to increase. Any downward force applied to the member B will cause the pressure of the curved portion 45 upon the lobe of the ear to be increased and therefore to resist the separating action.

When it is desired to release the earring, compression is applied by the fingers either to the ringlike portion 40 or to the portions 42 and 44 so as to free these portions from their engagement with the top and bottom walls of the opening 30, and this action will tend to free the member B of the compression action imposed by the upper and lower edges of the opening 45 and permit the earring to be removed.

Having thus described my invention and illustrated its use, what I claim as new and desire to secure by Letters Patent, is:

1. An earring comprising a U-shaped ornament-carrying member adapted to embrace the edge of the lobe of the ear, one of the legs of said member having an opening therethrough and a locking member adapted to be received in said opening for sliding adjustment therethrough, said locking member comprising two relatively yieldable fingers in superimposed relation and di-

verging outwardly, one of said fingers being adapted to engage the upper edge of the opening and the other the lower edge of the opening whereby the movement of said locking member to an ear lobe releasing position will be resisted by the increased pressure exerted thereon as the result of said movement.

2. An earring comprising a U-shaped member adapted to embrace the edge of the lobe of an ear, one of the legs of said member having an opening therethrough and a locking member adapted to be received in said opening for sliding adjustment therethrough, said locking member comprising two relatively yieldable fingers in superimposed relation and diverging outwardly, one of said fingers being adapted to engage the upper edge of the opening and the other the lower edge of the opening and one of said fingers being provided with a curved inner portion adapted to engage the lobe of the ear whereby the movement of said locking member to an ear lobe releasing position will be resisted by the increased pressure exerted thereon as the result of said movement.

25 3. An earring comprising a U-shaped member adapted to embrace the edge of the lobe of an ear, one of the legs of said member having an opening therethrough and a locking member adapted to be received in said opening for sliding adjustment therethrough, said locking member comprising two relatively yieldable fingers in superimposed relation, said fingers each comprising portions at an outwardly diverging angle to each other and a curved end portion, one of said outwardly diverging portions being adapted to engage the upper edge of the opening and the other the lower edge of the opening whereby the movement of said locking member to an ear lobe releasing position will be resisted by the increased pressure exerted thereon as the result of said movement.

4. An earring comprising a U-shaped member adapted to embrace the edge of an ear lobe, one of the legs of said member carrying the head of the earring which is visible and positioned on the exterior of the lobe, and the other leg having an opening therethrough and a locking member engaged through said opening, said locking member having an enlarged head to prevent separation from the leg and two yieldable fingers presented in the space between the legs of the first mentioned U-shaped member and normally in spread-apart relation, said two fingers of said locking member presenting surfaces which engage the opening and which diverge inwardly toward the earring head, whereby the locking member will normally be retained in its innermost or locking position and can be moved outwardly from that position only by moving the two yieldable fingers into closer adjacency to reduce the angle of divergence of their outer surfaces.

5. An earring comprising a body member and a locking member, the body member being U-shaped and having an earring head at the end of one of the legs and an opening through the end of the other leg, said locking member having an enlarged head at one end and two inwardly diverging fingers in superimposed relation extending inwardly from said end and connected to the head by a constricted neck, said locking member being engaged through the aforementioned opening to present one of the two aforementioned fingers in opposition to the earring head, whereby the locking member will normally

take a position wherein its constricted neck is engaged through and in opposition to the opening and the fingers are presented to lock the first mentioned U-shaped member to the lobe of the ear and the release of the locking member can be effected only by pressing together the two aforementioned fingers so as to decrease the angle of divergence between their two outer surfaces to an extent where the fingers can be moved through the opening to release the earring.

6. An earring comprising an ornament-carrying member and a member for locking said first mentioned member to the lobe of an ear, said ornament-carrying member being U-shaped and being so formed that it can be spread to embrace the edge of the lobe of the ear and one of its legs being provided with an opening therethrough, said locking member being made of a strip of resilient material doubled over upon itself so as to provide a ringlike head at one end and fingers projecting therefrom, said fingers diverging outwardly and each being provided with an end curved in the same general direction and said fingers being of a width so that they can be received through the aforementioned opening in one of the legs of the ornament-carrying member for free sliding movement therein, the height of the opening being such that the diverging fingers are always under compression which increases as the locking member is moved outwardly through the opening whereby, when the assembly of the ornament-carrying member and the locking member are engaged about the lobe of the ear, the said compression action upon the two diverging fingers will tend to force the locking member inwardly into engagement with the lobe of the ear.

7. An earring comprising an ornament-carrying member and a member for locking said first mentioned member to the lobe of an ear, said ornament-carrying member being U-shaped to embrace the edge of the lobe of the ear, one of its legs being provided with an opening therethrough, said locking member comprising a head at one end and fingers projecting therefrom, said fingers being made of resilient material and diverging outwardly and each being provided with an end curved in the same general direction and said fingers being of a width so that they can be received through the aforementioned opening in one of the legs of the ornament-carrying member for free sliding movement therein, the height of the opening being such that the diverging fingers are always under compression which in-

creases as the locking member is moved outwardly through the opening whereby, when the assembly of the ornament-carrying member and the locking member are engaged about the lobe of the ear, the said compression action upon the two diverging fingers will tend to force the locking member inwardly into engagement with the lobe of the ear.

8. An earring comprising an ornament-carrying member and a member for locking said first mentioned member to the lobe of an ear, said ornament-carrying member being U-shaped to embrace the edge of the lobe of the ear, one of its legs being provided with an opening therethrough, said locking member comprising a head at one end and fingers projecting therefrom, said fingers being made of resilient material and diverging outwardly and one of the fingers having its outer portion curved, said fingers being of a width so that they can be received through the aforementioned opening in one of the legs of the ornament-carrying member for free sliding movement therein, the height of the opening being such that the diverging fingers are always under compression which increases as the locking member is moved outwardly through the opening whereby, when the assembly of the ornament-carrying member and the locking member are engaged about the lobe of the ear, the said compression action upon the two diverging fingers will tend to force the curved portion of the locking member inwardly into engagement with the lobe of the ear.

9. An earring comprising a U-shaped ornament-carrying member adapted to embrace the edge of the lobe of an ear, one of the legs of said U-shaped ornament-carrying member having an opening therethrough and a locking member to be received in said opening for securing the ornament-carrying member attached to the ear lobe, said locking member being adjustable from ear-locking position to ear-releasing position and comprising means which engage portions of the edge of said opening to resist movement of said locking member to ear lobe releasing position to a degree which increases with the increase in the aforementioned releasing movement, whereby the ornament-carrying member will be secured against accidental release from the ear lobe, and means for rendering ineffective the engagement of the aforementioned means with the edge of the opening to permit the purposeful movement of the locking to its ear-releasing position.

LOUIS HOFFMAN.
